UNITED STATES PATENT OFFICE

ALEXANDER HOSIG, OF BLACKHAWK, WISCONSIN

DOOR FASTENER

Application filed May 13, 1929. Serial No. 362,764.

This invention relates to new and useful improvements in door fasteners.

One of the objects of my invention is the provision of a novel type of door fastener which is especially adapted for use on barn doors, garages and similar places where it is desirable to have a comparatively heavy type of fastener for securely retaining the doors in a closed position and which will 10 securely hold the door against movement until the fastener is manually actuated to release the door.

Another object of my invention is the provision of a door fastener so constructed and arranged that a padlock or similar type of lock may be quickly and readily applied thereto for retaining the fastener and also to provide means whereby the fastener is retained in a locked position through the 20 medium of a pivoted stop member designed to engage the movable locking member of the fastener, so as to retain the fastener in a locked position.

A further object of my invention is the provision of a door fastener comprising a cam shaped engaging member carried by the door frame with a pivoted locking bar carried by the door for engagement with the cam face member with the pivoted locking 30 member provided with handles at each end thereof disposed upon opposite sides of the door whereby the fastener may be actuated from either side of the door, the door however, carrying a pivoted stop for engagement with the locking member to retain it in locked engagement with the cam member.

With the above and other objects in view, the invention consists in the novel features of construction, the combination and arrangement of parts hereinafter more fully set forth, pointed out in the claims and shown in the accompanying drawings wherein:

Figure 1 is a longitudinal sectional view 45 of a door illustrating the application of my improved fastener; and,

Figure 2 is a horizontal view.

In the accompanying drawings, 1 indicates the door frame and 2 the door adapted to close the opening in the frame. Sup-

ported by the frame 1 adjacent the door opening is a semi-circular plate 3, the arcuate edge of which is disposed at an angle relative the body of the plate and provides an engaging rim 4. This rim 4 extends at 55 an angle relative the frame 1, as shown in Figure 2.

The door 2 is provided with a transverse opening, and arranged upon the exterior face of the door is a plate 5 having a sleeve 6 extending through the opening in the door, and pivotally mounted within this sleeve is an angular member providing a locking arm 7 and an operating arm 8. These arms 7 and 8 extend at an angle to 60 each other and at an angle to the pivot point 9.

The inner end of the arm 7 is reduced and threaded, as shown at 10, and screwed onto the threaded portion is a collar 11 carrying a hook-like engaging member 12. The collar 11 is preferably carried by the handle 13 which is internally threaded at its inner end for engagement with the threads 10. 70

From the above, it will be apparent that the locking arm 7 not only carries the hook-shaped engaging member 12, but the handle member 13, whereby to manipulate the locking arm 7. 75

It will be noted that the relative position of the arm 7 with regard to the pivot 9 permits the arm to swing in the arc of a circle, but due to the fact that the pivot point 9 is arranged above the center of the plate 3, the hook-like member will move 80 away from the outer edge of the plate as the arm 7 is swung upwardly, but when the arm 7 moves downwardly, the hook-like member will engage the angularly disposed rim 4 of the plate 3 and have a tendency 85 to grip or frictionally engage therein to lock the arm 7 against further movement. 90

The arm 8 which extends downwardly through the door 2 is provided with a handle 14 whereby the arms 7 and 8 may be simultaneously operated, the handle 8 being provided for actuating the locking arm 7 from the outside of the door, while the handle 13 is provided for actuating the arm 7 from the inside. 95 100

When the arm 7 is swung to an unlocked position and entirely away from the plate 3, it normally rests within a longitudinal recess 15 formed in the inner face of the door 2. This position of the arm 7 also limits the pivotal movement of both arms 7 and 8.

When the handle member 14 is grasped from the outside of the door and moved upwardly, the arm 7 is moved downwardly 10 engaging the hook member 12 with the rim 4. After the hook 12 has been tightly engaged with the rim 4, a pivoted stop 16 is swung upwardly into vertical position to engage beneath the arm 8 as shown in 15 Figures 1 and 2. This stop 16 will prevent any tilting movement on the part of the arms 7 and 8 so as to retain the hook member 12 in frictional contact with the rim 4 which in turn will retain the door 2 in 20 locked position.

The stop comprises a metal arm having its upper end bent at right angles to form an engaging part to be positioned beneath the arm 8, and the main part of the stop 25 is further provided with a lateral extension 18 forming a finger piece which can be readily grasped for moving the stop beneath the arm 8, or moving the same from the arm 8. This stop member 16 is pivotally mounted at 19 by means of a rivet or thread which may be engaged with the plate 5 or extended through the door if desired.

Secured to the plate 5 and arranged adjacent the sleeve 6 is a staple 20 which, when the arm 8 is moved to its locked position, as shown in Figure 1, can receive the shackle of 35 a padlock or the like, said shackle embracing the arm 8 as well as one side of the staple 20 in order to provide additional means for locking the arm 8 against movement.

It will be apparent from the foregoing that my improved fastener can be used either on barn doors, garage doors or in any place 45 where the device may be applicable. In the operation of the device, it will be noted that it may be readily actuated from the interior or exterior of the door. In other words, if the stop member 16 is thrown to an inoperative position, a party may readily unfasten 50 the door by grasping the handle member 14, moving the arm 8 downwardly which in turn will move the arm 7 upwardly, disengaging the hook member 12 from the rim 4 and as the arm 7 is swung to an entirely unlocked 55 position, it will come to rest in the recess 15. The door may then be swung open by pulling outwardly on the handle 14. After the party passes through the door, the handle 60 member 13 may be then grasped to move the arm 7 downwardly again engaging the hook 12 with the arm 4. This will retain the door in a secured position while the party is in the building, and as the arms 7 and 8 are 65 not securely locked against movement, the

party may readily disengage the hook 12 from the rim 4 from the inside.

It will be apparent that the arms 7 and 8 may be readily locked against accidental displacement through the medium of a stop member 16, but when it is desired to securely lock the device against manipulation by unauthorized persons, a padlock is engaged with the staple 20 and the arm 8 so that it will be impossible to actuate the arm 8 without releasing the padlock.

The plate 3 may be secured to the side of the door or to the frame 1 in any suitable manner, but in the present instance I have illustrated lag screws 21 which pass through 80 the plate and engage with the door.

While I have shown and described the preferred embodiment of my invention, it will be apparent that slight changes may be made in the construction when putting the invention into practice without departing from the spirit of the same or the scope of the appended claims.

I claim:

1. A device of the class described including a stationary arcuate cam plate, having an angularly disposed engaging face, angularly positioned arms having their inner ends pivotally mounted on a movable member and adapted to be disposed adjacent the straight edge of the plate, a hook member carried by one of said arms for engaging the cam surface of the plate, and a handle member at the outer ends of both arms for engaging and disengaging the hook member with the cam plate.

2. A device of the class described including an arcuate cam plate having a straight edge, and an inclined engaging face, pivoted arms carried by a movable member, one of said arms being disposed at an angle to the pivot point, a hook member carried by said arm for engagement with the cam face of the plate, a handle carried by the outer ends of both arms whereby to actuate said hook member from either side of the movable member, and a stop member carried by the movable member and adapted to engage one of said arms for retaining the hook member in locking engagement with the cam plate.

3. A lock of the class described including an arcuate cam plate having a straight edge and an inclined engaging face, a supporting sleeve carried by a movable member, a locking member pivotally mounted in the sleeve with its pivot point above the transverse center of the cam plate, said locking member including angular arms extending from opposite sides of the sleeve, a hook member carried by one of said arms and adapted to cooperate with the engaging face of the plate for retaining the movable member against movement, a handle at the outer end of each arm whereby to impart movement to the hook member for engaging the same with

the cam plate or disengaging the same therefrom and a pivoted stop member carried by the sleeve and having a lateral portion adapted to engage beneath one of said arms 5 for retaining the locking member against movement when engaged with the cam plate.

In testimony that I claim the foregoing I have hereunto set my hand at Blackhawk, in the county of Sauk and State of Wisconsin.

ALEXANDER HOSIG.
